UNITED STATES PATENT OFFICE.

JULIO E. GARCIA-SANCHEZ, OF NEW YORK, N. Y.

STEERING APPARATUS FOR VESSELS.

SPECIFICATION forming part of Letters Patent No. 427,845, dated May 13, 1890.

Application filed October 1, 1889. Serial No. 325,653. (No model.)

To all whom it may concern:

Be it known that I, JULIO E. GARCIA-SANCHEZ, of Venezuela, South America, now residing in the city, county, and State, of New York, have invented a new and Improved Steering Apparatus for Vessels, of which the following is a full, clear, and exact description.

This invention relates to steering apparatus for vessels, and has for its object to provide a steering apparatus by means of which a vessel may be steered simultaneously at the stern and bow, and the vessel thereby more effectually directed.

The invention consists in a steering apparatus and in details thereof for steering vessels simultaneously at the stern and bow, as hereinafter described and claimed.

Reference is to be had to the accompanying drawings, forming a part of this specification, in which similar figures of reference indicate corresponding parts in all the views.

Figure 1 is a view of the bow of a vessel, showing a portion of the steering apparatus constructed and arranged in accordance with this invention. Fig. 2 is a detail view of the rudder, shown in Fig. 1, detached. Fig. 3 is a plan view, partly in section, of the bow of the vessel and steering apparatus shown in Fig. 1. Fig. 4 is a detail view, partly in vertical section, of one of the rudder-hinges. Fig. 5 is a plan view thereof, and Fig. 6 is a plan view of the vessel with the deck at the bow broken away and the entire steering apparatus disclosed.

In carrying out this invention the hull 1 of a vessel has its bow 2 provided with a rudder 3, located in and forming part of the bow, the tapering edge 4 of the rudder, when the latter is in normal position, serving as the cut-water of the vessel. The top of the rudder 3 is formed with the flat portion 5, located beneath the horizontal cut-away portion 6 of the bow, having a recess 7 at its rear end to permit of the movement of the oval portion 8 of the double-armed tiller 9, secured to the top of the rudder and located in the recess 7. The rudder 3 is hinged to the vertical portion 10 of the bow in any suitable manner, and as here shown by means of a number of hinges 11, consisting of the metallic tongue portions

11' and socket portions 11², having securing tangs or straps 12 with bolt-holes 13. The socket portions 11² of the hinges are let into recesses in the vertical oval edge 14 of the rudder, with their straps 12 projecting into slots in the rudder and secured by bolts passing through the holes 13. The tongue portions 11' are secured to the vertical portion 10 of the bow by their straps 12 projecting into slots therein and secured by bolts, and the hinged portions 11' and 11² are connected together by a rod 15, (shown in dotted lines in Fig. 1,) extending through aligning-holes 16' in the portions 11' 11² of the hinges, the tongue portions 11' resting in the socket portions 11². The upper end of the rod 15 terminates in a square portion 16, projecting through the metallic step 17 on the rudder.

The tiller 9 is attached to the rudder by means of a square socket 18 engaging the square portion 16 of rod 15, the tiller resting in the step 17 and against the shoulder 17^a thereof. The tiller may be further secured in place by bolts 9^a passing through the tiller and engaging the step 17, which step is in turn held to the rudder in a similar manner to the socket portions of the hinges. The lower stepped corner 19 of the rudder rests on a step 20, secured to the bow and similar in construction to the tongue portion 11' of the hinges 12.

The hull 1 is provided with the usual form of rudder at the stern and having a rearwardly-extending tiller 21.

The rudder at the stern is connected with the rudder 3 at the bow and operated simultaneously therewith by means of the following apparatus.

Connected with the arms of the double tiller 9 are tiller-ropes 22, passing through openings 23 in the rail 24 of the vessel and over pulleys 25 in the openings 23 to a drum 26, mounted in standards 27 and 28 on the forward part of the deck of the hull 1.

The tiller-ropes 22 are reversely wound on the drum 26, so as to turn the rudder 3 in opposite directions.

The standard 28 is formed at its top with a rack 29 in the form of a segment of a circle, and the shaft of the drum 26 has a vertical lever-handle 30, with a locking-pin 31, having an operating-handle 32, which is in turn piv-

oted to the lever 30. By this means the pin 31 may be thrown into engagement with the rack 29 to lock the rudder 3 in position.

Located above the rudder-post of the rudder at the stern is a drum 34, having a steering-wheel 35, the axle of the drum 34 and steering-wheel 35 being mounted in standards 36 and 37 on the deck of the vessel.

To the end of the tiller 21, which extends and moves beneath the standard 37, are secured one end of tiller-ropes 38, each of which passes over a pulley 39, attached to the rail 24 of the vessel and a second pulley 40, attached to the deck of the vessel on either side of the rudder-post, and are reversely wound at their other ends to the drum 34. To the drum 34 are also reversely wound one end of steering-ropes 41, which pass over pulleys 42, secured to the rail 24, and then extend forward along side of the rail to the forward part of the vessel, where they pass over the pulleys 25 and can be connected to the tiller-ropes 22 a little forward of the openings 23 in the rail.

It will thus be seen that by means of the steering apparatus hereinbefore described the vessel may be simultaneously steered at the stern and bow by turning the wheel 35. With the two rudders in normal position to steer a straight course, the pin 31 being out of engagement with the rack 29, upon turning the wheel 35 in one direction or the other to change the course the steering-ropes will be acted upon to simultaneously deflect or turn the rudders at an angle to the same side of the vessel. By this means steerage-way will be given to both the bow and stern of the vessel, and the latter will be made to more readily and effectively answer her helm.

It is obvious that in case it is desired to move the vessel backward steerage-way may be also effectively had in the opposite direction from the forward movement.

While I have set forth a specific arrangement of the steering apparatus, I do not desire to limit myself thereto, as it may be varied without departing from the essential features of the invention, which consists in rudders located at the bow and stern and apparatus for simultaneously operating the rudders to steer the vessel at the bow and stern.

Having thus described my invention, what I claim as new, and desire to secure by Letters Patent, is—

A steering apparatus for vessels, consisting, essentially, of a rudder having a double tiller located at the bow of the vessel, steering-ropes 22, connecting said double tiller with the drum 26, upon which said ropes are reversely wound, pulleys 25, drum 26, provided with a suitable handle and locking device, a rudder with a rearwardly-extending tiller located at the stern of the vessel, a drum 34 and steering-wheel 35, suitably mounted in the after part of the vessel, steering-ropes 38, connecting the tiller of the stern-rudder over suitable pulleys 39 65 40 with the drum 34, upon which they are reversely wound, and ropes 41, reversely wound upon the drum 34 and adapted to connect with the steering-ropes 22, so that the rudders at the bow and stern of the vessel may be simultaneously operated, substantially as described.

JULIO E. GARCIA-SANCHEZ.
